UNITED STATES PATENT OFFICE.

MAX RICHARD PARTZSCH, OF DRESDEN LÖBTAU, GERMANY.

MACHINE FOR APPLYING METAL STRIPS TO BOXES.

SPECIFICATION forming part of Letters Patent No. 623,332, dated April 18, 1899.

Application filed September 28, 1898. Serial No. 692,120. (No model.)

To all whom it may concern:

Be it known that I, MAX RICHARD PARTZSCH, a subject of the King of Saxony, residing at Dresden Löbtau, Saxony, Germany, have invented certain new and useful Improvements in or Relating to Means for Feeding Securing or Strengthening Strips in Box-Making and Similar Machines, (for which application for Letters Patent has been made in England June 20, 1898; in Hungary June 21, 1898; in France June 20, 1898; in Austria June 17, 1898, and in German Empire June 8, 1898,) of which the following is a specification.

The device for feeding securing-strips or strengthening-strips in box-making and similar machines according to this invention is based on the principle, which is well-known in itself, of effecting the advance of the strip toward the hammer by means of a guide-lever, the (circular) path of which does not coincide with that of the hammer. Hitherto, however, the strips in machines of this kind have been generally gripped at a point at the back and pushed forward through a guide, which necessarily presupposes a certain amount of rigidity in the strip. It is found that toothed-metal clamping-strips of slight rigidity bend up and buckle when pushed through, thereby jamming in the guide or becoming bent at their projecting points, whereby the advance becomes uncertain and inexact or impossible. Flexible strips of paper or fabric for gluing to the parts to be joined or strengthened cannot be fed in this way at all. Metal strips require in such machines a long and carefully-machined guide in order to prevent the strip from bending.

A secure and exact feeding of the strip and a cheaper and simpler construction of the machine are attained according to this invention by taking hold of the continuous clamping-strip at or near its front end and by pulling it forward. This is effected by passing the strip through a guide-opening at one end of the hammer, seizing the same beyond the said opening (in the sense of the direction of movement of the strip) by gripping or clamping devices movable in guides on the hammer-head and at the same time drawing the strip forward, owing to the relative movement of the hammer and guide-lever.

The accompanying drawings illustrate by

way of example a construction of the machine according to this invention, in which the strip is caused to advance during the descent of the hammer.

Figure 1 is an elevation of a machine for applying or nailing on sheet-metal strips provided with the feeding device according to this invention, the hammer being shown in its raised position. Fig. 1^a is a detail view. Fig. 2 shows the head of the hammer, a front portion of the hammer-arm in section, and a front portion of the anvil, with work placed on it, on a considerably larger scale than in Fig. 1, the hammer being here shown in its lowered position. Fig. 3 is a back view, and Fig. 4 a vertical cross-section, of the hammer-head on the line 4 4 of Fig. 2, the two figures 3 and 4 being on the same scale as Fig. 2. Fig. 5 represents in front elevation the clamping device or pawls. Fig. 6 shows the same in section on the line 6 6 of Fig. 5; and Fig. 7 shows one of the pawls viewed in the direction indicated by the arrow, Fig. 5. Figs. 5, 6, and 7 are shown on a larger scale than that of Figs. 2, 3, and 4.

The machine illustrated by way of example consists of a hammer A, which by means of its arm A' is pivoted about a pin a and can be lowered on the anvil B by depressing a treadle A² and rod a' in opposition to the action of a spring a². As the machine represented is intended for securing or applying corner-strips, the anvil B has inclined sides and the hammer is provided with corresponding longitudinal grooves of right-angular cross-section, Fig. 4. For applying flat strips both the anvil and hammer must be flat. The work W is placed in the well-known manner on the anvil from the front, the hammer is lowered, whereupon the clamp-strip S is advanced and the length corresponding to the work cut off and applied. The strip S unrolls from a spool S'.

Inside the cover 1, Figs. 2 and 3, there is guided in a groove in the rear end of the hammer a part 2, which forms the open guide for the clamping-strip and at the same time the lower blade of a pair of cutters. The opening in the part 2, having the shape of an inverted U, Fig. 3, and corresponding to the cross-section of the strip S, Fig. 4, forms the guide proper, while the sharp edge 2^a at the

front end of this guide forms the cutter-blade, as stated. With said blade co-operates as the upper blade a plate 3, secured to the hammer A in front of the part 2, and provided with 5 a recess having the shape of an inverted V. A spring 4, Fig. 2, in a fixed cap 5, drives, when the hammer is raised, the guide 2 as far down as its pin 6 can move downward in the slot in the cover 1, Fig. 3. When the 10 hammer is lowered, the part 2 strikes the anvil first, while the hammer still continues to descend. The relative movement of the cutter parts 3 and 2^{2a} causes them to become operative.

15 At 7 there is pivoted to a projection of the part 2 a pawl 8, bifurcated in front, Figs. 2 and 3, which engages with its two teeth the recesses of the strip S (not shown in Fig. 3) and prevents it from moving back to the 20 right.

9 is a spring acting on the pawl to keep it depressed.

In the guides formed by the lateral grooves in the hammer A and by the covering-plates 25 10, Figs. 2 and 4, there are arranged movable slide-blocks 11, to which are secured the bosses 12 of the bifurcated guide-lever D. The two feed-pawls 13 are pivoted in the rear continuations of the blocks 11 in a plane at 30 right angles to that of the movement of the strip. The heads of these pawls (shown more fully in Figs. 5 to 7) are such that they form teeth 13^a, beveled only on one side, and the strip S is supported at the top and bottom 35 by the remaining edges. The teeth 13^a are pressed inward, by springs 14 acting on the pawls, into engagement with the teeth or intervals between teeth or between the projections of the clamping-strip. They grip the 40 strip when moving in the direction indicated by the arrow, Fig. 6, while in the opposite direction they open outward without exercising any action on the strip. When the hammer strikes the anvil, the pawls being 45 rounded off at their heads are forced outward by the cam-faces of the hammer, and thus brought outside the path of the hammer.

Assuming that the guide-lever D is pivoted about the center d and the hammer-head A 50 is in the position shown by full lines in Fig. 1, in which position the hammer is adapted to completely cover the anvil when depressed, the two pawls 13 13 are at the rear end of the hammer and engage with one of the first teeth 55 of the strip S, slightly projecting through the guide-opening in the sliding piece 2. When the hammer is depressed, the slide-blocks 11 are caused to advance in the guides in the hammer by the oscillation of the guide-lever 60 about its pivot d, and as the pawls are operative when moving in this direction the strip will be advanced to the extent equal to the length of the hammer. (See arc I III III, Fig. 1.) The same effect would be produced if the 65 hammer were replaced by a vertically-guided stamp or plunger, for even in this case the path I III III cuts the vertical path of the ham-

mer, and the required relative movement takes place if the dimensions be suitably chosen.

The length of the strip to be fed can be easily altered as desired in the construction described by making the hammer-head adjustable on the arm A' and the guide-lever D movable in the manner to be described. For 70 this purpose the arm A' is provided in front with a longitudinal passage or slot, in which are adjustable bolts 15, Figs. 1 and 2. The shorter the length of strip to be cut and applied the farther forward must the hammer-head A be placed, the bolt 15 being tightened when the head is correctly adjusted. A side 75 of the head A can be graduated according to any desired system of measurement or, still better, according to the number of teeth to be applied at each operation. Opposite this scale, an example of which is clearly indicated in Fig. 2, there is arranged on the arm A' a fixed pointer 16. The lower end of the guide-lever D works freely through an opening in 80 a block d, formed with side extensions 17, by which it is supported and upon which it turns. A spring 18 (which can be replaced by a weight) tends to press the guide-lever downward until the shoulder 19 rests against 85 the block d. In this position the guide-lever can only swing concentrically with the part d. When the hammer is moved more to the front—for instance, as indicated by dotted lines in Fig. 1—the guide-lever also takes up 90 when the hammer is raised the position shown in dotted lines, the spring being compressed and the shoulder 19 being situated above the part d. When the hammer is being lowered, there is at first no movement of the two pawls 95 toward the part of the hammer. On the contrary the two pawls swing in the arc IV II concentrically with a, as the spring 18 draws the guide-lever as far down as is allowed by the descending hammer-head. In this way 100 the two pawls remain, therefore, in their rear position, determined by the edges x of the slide-blocks 11, resting against the edges x' of the part 2, Fig. 2. The shoulder 19 having, however, reached, at the point 11, the 105 block d during the remainder of the travel II III the movement of the strip takes place 110 in the manner described. The projection of the path II III onto the anvil corresponds to the length fed.

In the construction described the feeding of the strip is effected during the descent of the hammer. It could, however, take place 115 equally well during the ascent if the center of rotation of the guide-lever D were moved upward beyond the center of rotation a of the hammer. The feeding would also take place during the ascent of the hammer, if the feeding were to take place from the front and the center d were below the center a. Otherwise 120 it would take place during the descent. If the feeding is effected from the front, the spool S' for the strip is arranged above the machine and the strip is guided by a suit-

ably curved guide to the guide-openings 2, which must then of course also be arranged in front.

If the apparatus described is to be used for strips to be affixed by cementing them onto the material, the pawls 13 must be replaced by other clamping devices adapted to seize the strip during its advance or by pins penetrating into the strip.

10 I claim--

1. In a machine for applying metal strips to boxes, the combination with the hammer adapted to be reciprocated back and forth, the guide-opening at one end of the hammer, through which the strip passes, and means for feeding and positioning the strip located on the hammer-head at a point beyond said guide-opening; substantially as described.

2. In a machine for applying metal strips to boxes, the combination with the reciprocating hammer, the guide-opening at one end of the hammer-head through which the strip passes, mechanism for feeding the strip forward located at a point on the hammer-head beyond the guide-opening, and the bifurcated pawl pivoted to the rear end of the hammer-head and engaging the strip on each side to prevent its backward movement; substantially as described.

3. In a machine for applying metal strips to boxes, the combination with the reciprocating hammer, the guide for the strip, located at one end of the hammer, the blocks sliding in guides on the sides of the hammer-head, the strip-feeding device carried by the slides, the oscillating guide-lever connected to the slides, whereby the slides will be operated owing to the relative movement of the hammer and the arc of oscillation of the

40 guide-lever; substantially as described.

4. In a machine for applying metal strips to boxes, the combination with the reciprocating hammer, the slides carried thereby, the oscillating guide connected to the slides,

pawls carried by the slides, springs for holding said pawls in contact with the strip to grip the same as the hammer descends.

5. In a machine for applying metal strips to boxes, the combination with the reciprocating hammer, the slides carried by the hammer-head mechanism for reciprocating said slides, the pawls pivoted to the slides in a plane at right angles to that of the movement of the strip, springs for pressing said pawls inward, whereby as the hammer descends, the pawls will grip the strip and the strip be fed, but when the hammer ascends, said pawls will open out and release the strip; substantially as described.

6. In a machine for applying metal strips to boxes, the combination with the reciprocating hammer, the blocks sliding on the hammer-head, mechanism for operating said blocks, the pawls pivoted to said blocks to swing outward, and having teeth at the lower end beveled on one side only, springs for pressing the pawls into engagement with the strip, whereby when the block is moved forward, the teeth will grip and feed forward the strip, but will be forced outwardly by the strip when the block is moved backward; substantially as and for the purpose set forth.

7. In a machine for applying metal strips to boxes, the combination with the reciprocating hammer, the anvil, the slides carried thereby, the pawls pivoted on said slides, having their heads rounded off, whereby when said pawls strike the anvil, they will be forced outward out of the path of the hammer; substantially as described.

In witness whereof I hereto set my hand in the presence of the two subscribing witnesses.

MAX RICHARD PARTZSCH.
